CATHODE RAY DEVICE

Hans Erich Hollmann, Berlin-Lichterfelde, Germany, assignor to Radio Patents Corp., New York, N. Y., a corporation of New York

Application April 30, 1937, Serial No. 139,913
In Germany May 23, 1936

6 Claims. (Cl. 250—162)

The present invention relates to cathode ray tubes as used for oscillographic recording and like purposes, and is more particularly concerned with an improved construction for and method of operating tubes of this character.

5 The known cathode ray tubes used for oscillographic and like purposes usually comprise means for producing a concentrated beam or pencil of electrons, a fluorescent screen arranged for the electron beam to strike against to produce a luminous recording spot thereon, and an arrangement such as a pair of electrostatic deflecting plates or magnetic field coils for deflecting the electron beam in accordance with variations of an electric controlling potential or current to obtain a visual record upon the fluorescent screen.

10 As is well known, the sensitivity of deflection of the electron beam in a cathode ray tube of the above character employing a pair of electrostatic deflecting plates may be expressed by the following theoretical equation:

$$s = E \frac{1}{d} \frac{L}{2E_a}$$

25 wherein s represents the deflection of the luminous recording spot on the screen from its central or zero position; E is the deflecting voltage impressed upon the deflecting plates; l is the length of the deflecting plates taken in the direction of the electron beam; d is the distance between the deflecting plates; L is the distance between the center of the deflecting field and the fluorescent screen, and E_a represents the anode or acceleration potential or the volt velocity of the beam at the point of deflection.

30 From the above equation it is seen that the deflection s of the luminous recording spot depends substantially on the geometry of the tube; that is, the so-called "field factor"

$$\frac{1}{d}$$

35 of the deflecting field and the distance L between the deflecting field and the fluorescent screen. This distance L is fixed by the size of the tube on the one hand and by the space occupied by the cathode and the acceleration or electron lens arrangement on the other hand plus an additional spacing distance between the electron lens and the deflecting arrangements. Furthermore, it is seen that no advantage is gained by an excessive increase of the length l of the deflecting plates since such an increase results in a decrease of the distance L . Moreover, a minimum

40 distance d is required between the deflecting plates to allow the electron beam to sweep over the entire useful, effective area of the screen and to prevent a cutting off of the beam in its extreme deflecting positions. Similar limitations apply to a tube using a magnetic instead of an electrostatic deflecting field.

45 The sensitivity of deflection of the luminescent spot in a cathode ray tube by a controlling potential or current is thus limited and it has not been possible to increase the sensitivity beyond the limit value determined by the geometry of the tubes constructed in a manner known in the prior art.

50 Accordingly, an object of the invention is the provision of a new construction for and a method of operating cathode ray tubes for oscillographic and like purposes, whereby the sensitivity of deflection of the electron beam may be increased substantially beyond the limit value obtainable with constructions of the type known in the prior art.

55 With this object in view, the invention contemplates the employment of a flat electron beam in place of a round beam or pencil used in the conventional type of cathode ray oscilloscopes. Such a beam produces a luminous streak or line of light upon the fluorescent screen which is displaced parallel to its length by means of a suitable deflecting arrangement for the electron beam, such as a pair of electrostatic deflecting plates connected to the source of the controlling potential or current. In order to obtain a luminous recording spot there is further provided in accordance with the invention, a screen or mask having a slit or the equivalent thereof arranged at an angle with the flat electron beam or line of light produced thereby upon the luminescent screen. In this manner, only a luminous spot or point is produced upon the recording screen at the intersection of the line of light with the slit or its equivalent, which spot will move along the slit as the electron beam is deflected in the manner set forth hereinbefore.

60 Alternatively, the screen may be coated with the streak or line of luminescent material arranged at an angle with the line of light produced thereon by the electron beam.

65 Further objects and features of the invention will become more apparent from the following detailed description taken with reference to the accompanying drawing forming part of this specification and wherein:

70 Figure 1 illustrates schematically a cathode ray tube and a recording system therefor con-

structed in accordance with the invention, and Figure 2 is a side view of the tube shown in Figure 1.

Referring to the drawing, there is shown a cathode ray tube comprising an evacuated vessel or envelope 10 enclosing a cathode 11 which in the example shown has the form of a wire wound into a narrow spiral and heated to electron emitting temperature in any suitable manner such as by means of a heating battery 12. The cathode is surrounded by a frame 13 having an open front and serving as an initial concentration electrode to produce a flat electron beam leaving the cathode such as indicated by the dotted lines in the drawing. For this purpose the frame 13 is negatively biased in a known manner with respect to the cathode such as by means of a biasing battery or the like as shown at 14. The flat electron beam after leaving the cathode is accelerated and focused upon the fluorescent screen 23 arranged at the opposite end of the tube, such as by means of a pair of accelerating or anode electrodes 15 and 16 having slits arranged in line with the cathode or electron beam produced thereby and biased positively with respect to the cathode by means of an anode battery 17 or the like. The anode 15 is connected to a lower potential point on the battery 17 than the anode 16 whereby both anodes from what is known as an electron lens adapted to produce a sharp electron image of the slit, resulting in a luminous streak 18 upon the fluorescent screen. This streak or line of light is deflected parallel to, or in a direction transverse to its length in accordance with the potential variations to be recorded by means of a pair of deflecting plates 19 and 20 arranged parallel to and at opposite sides of the electron beam and connected with the source of deflecting potential to be connected to the input terminals 21. As is understood, any other well known deflecting arrangement such as a pair of magnetic deflecting coils may be provided in place of electrostatic deflecting plates for the purpose of the invention.

There is further provided, in accordance with the invention, a screen or mask 22 arranged in front of or behind the fluorescent screen 23 of the tube and having a slit shown at 24. In the example illustrated, the mask 22 is mounted against the outer wall of the tube and the slit 24 is arranged in a vertical direction in which case the cathode, electron lens, and deflecting plates have to be mounted in such a manner that the flat electron beam forms an angle with a vertical line. Thus, the line of light 18 when deflected in the manner described, intersects the slit 24 at different points thereby producing a recording spot which travels up and down in accordance with the variations of the deflecting potentials impressed upon the deflecting plates. The width of the slit 24 is preferably, although not necessarily, equal to the thickness of the electron beam or width of the luminous line 18 produced thereby to obtain a recording spot resembling as much as possible a circle as obtained in the ordinary type of cathode ray tube. In the example illustrated, the line 18 in the zero position intersects the slit 24 at its center whereby both positive and negative potential variations may be recorded with regard to a zero line or axis. If the beam is deflected, the luminous line will assume varying positions within the useful deflecting range between the extreme positions shown at 18' and 18''.

In order to produce a permanent oscillographic

record, the spot thus produced on the luminescent screen may be focused in a known manner upon the photographic film 25 or the like by means of an optical lens 26. The film 25 is moved continuously in a direction at right angle to the slit 24 as indicated by the arrow to provide a time axis for the curve or record obtained, and indicated at 27. As is understood, the movement of the film 25 may be in a direction forming an angle with the slit 24 differing from a right angle if a record is desired in a coordinate system other than rectangular coordinates, as in the case illustrated. It is further understood that any other arrangement of known type for producing a flat electron beam may be provided for the purpose of the invention in place of the specific arrangement shown.

The screen or mask 22 may be either a separate element provided with a slit 24 in the manner described or it may consist of a coating of lacquer or other material opaque to light rays (if the screen is mounted against the outside wall of the tube) or to electron rays if the mask is mounted against the inner wall of the tube in front of the fluorescent screen. Alternatively, a suitable screening substance may be applied to the fluorescent screw either before or after depositing the fluorescent substance with a slit like portion 24 kept free by means of a stencil or the like in a manner well understood.

By means of an arrangement and construction of the type described, it is possible to considerably increase the sensitivity of deflection of the recording spot beyond values obtainable in cathode ray tubes of standard design and construction. Thus, referring to Figure 2, it is seen that if the luminous line 18 is displaced parallel to its length by an amount a from its position 18' to position 18, the intersection point will move along the slit 24 from point A to point B; that is, it will travel a distance equal to

$$\frac{a}{\cos \alpha}$$

wherein α represents the angle between the slit 24 and a line forming a right angle with the line 18. The equation for the deflection S obtained with the new tube is therefore modified by substituting the distance travelled by the luminous spot in the equation for the standard tubes. This new equation will be as follows:

$$s = \frac{E}{\cos \alpha} \frac{1}{d} \frac{L}{2E_a}$$

As is seen therefrom, if $\alpha=0$ that is, if the slit 24 is arranged at a right angle to the luminous line 18, no increase in sensitivity is obtained since $\cos 0=1$. If α is 45° , the increase in sensitivity is about 1.4 times and when using an angle of 60° , the increase in sensitivity is doubled, while at an 30° angle the sensitivity obtained is 5.5 times that of an ordinary cathode ray tube. In this manner it is seen that the sensitivity may be increased considerably as compared with cathode ray tubes of known construction. A limit is determined only by the fact that the intersection point or recording spot in the case of large angles assumes an elongated rhomboidal shape in place of a more or less round spot which may impair the sharpness of the record or oscillogram obtained.

According to a further feature of the invention, the slit 24 may be given any shape differing from a straight line and following a predetermined function in order to obtain a record or oscillo-

graphic curve related to the deflecting potentials or currents in accordance with a desired law.

It will be apparent from the above that the invention is not limited to the specific constructions, arrangements of parts and methods of operation described and shown herein for illustration, but that the underlying novel concept thereof is susceptible of numerous modifications and variations coming within the broad scope and spirit of the invention as defined in the appended claims.

It is understood therefore that the description and drawing are to be regarded in an illustrative rather than in a limiting sense.

I claim:

1. In a cathode ray recording device, a source of electrons, means comprising an element having a narrow slit for concentrating the electrons emitted by said source into a beam of linear cross-section in line with said slit, means for deflecting said beam substantially parallel to its cross-sectional axis, a luminescent screen arranged to be impinged by said beam, and a mask overlying said screen and having a slit forming an angle with said first slit substantially differing from a right angle, thereby to produce a luminous recording spot moving across the slit of said mask in accordance with variations of a deflecting potential impressed upon said deflecting means.

2. In a cathode ray recording device, a source of electrons, means comprising at least one diaphragmatic electrode having a narrow slit for concentrating the electrons emitted by said source into a beam of linear cross-section in line with said slit, a pair of electrostatic deflecting plates arranged opposite and parallel to said beam in its normal position, a luminescent screen arranged to be impinged by said beam, and a mask overlying said screen and having a slit forming an angle with said first slit substantially differing from a right angle, thereby to produce a luminous recording spot moving across the slit of said mask in accordance with variations of a deflecting potential impressed across said deflecting plates.

3. In a cathode ray recording device, a source of electrons, means comprising at least one diaphragmatic electrode having a narrow slit for concentrating the electrons emitted by said source into a beam of linear cross-section in line with said slit, means for deflecting said beam substantially parallel to its cross-sectional axis, a luminescent screen arranged to be impinged by said beam, and a mask overlying said screen and having a slit forming an angle with said first slit substantially differing from a right angle, the line connecting the center points of both said slits coinciding with the normal axis of said electron beam, thereby to produce a luminous recording spot moving from the center of the slit of said mask in opposite directions in dependence upon variations in a positive or negative sense, respec-

tively, of a deflecting potential impressed upon said deflecting means.

4. In a cathode ray recording device, a source of electrons, means comprising at least one diaphragmatic electrode having a narrow slit for concentrating the electrons emitted by said source into a beam of linear cross-section in line with said slit, means for deflecting said beam substantially parallel to its cross-sectional axis, a luminescent screen, arranged to be impinged by said beam, and a mask overlying said screen and having a slit forming an angle with said first slit substantially differing from a right angle, both of said slits being of substantially equal width, thereby to produce a luminous recording spot moving across the slit of said mask in accordance with variations of a deflecting potential impressed upon said deflecting means.

5. In a cathode ray recording device, an envelope, a source of electrons disposed at one end within said envelope, means comprising at least one diaphragmatic acceleration electrode having a narrow slit for concentrating the electrons emitted by said source into a beam of linear cross-section in line with said slit, means for deflecting said beam substantially parallel to its cross-sectional axis, a translucent luminescent screen at the opposite end of said envelope impinged by said electron beam, and a mask overlying said luminescent screen and disposed on the outside of said envelope, said mask having a slit forming an angle with said first slit substantially differing from a right angle, thereby to produce a luminous recording spot moving across the slit of said mask in proportion to variations of a deflecting potential impressed upon said deflecting means.

6. In a recording system, a cathode ray device comprising an envelope, a source of electrons disposed at one end within said envelope, means comprising at least one diaphragmatic acceleration electrode having a narrow slit for concentrating the electrons emitted by said source into a beam of linear cross-section in line with said slit, means for deflecting said beam substantially parallel to its cross-sectional axis, a translucent luminescent screen at the opposite end of said envelope impinged by said electron beam, and a mask overlying said luminescent screen and disposed on the outside of said envelope, said mask having a slit forming an angle with said first slit substantially differing from a right angle, thereby to produce a luminous recording spot moving across the slit of said mask in proportion to variations of a deflecting potential impressed upon said deflecting means, a record carrier with means for continuously moving the same at an angle to the slit of said mask, and means for focussing the luminescent spot on said screen unto said record carrier.

HANS ERICH HOLLMANN. 60
